UNITED STATES PATENT OFFICE.

ARTHUR MILLS, OF SACRAMENTO, CALIFORNIA.

TRUCK-STAKE.

1,333,990.

Specification of Letters Patent. Patented Mar. 16, 1920.

Application filed April 7, 1919. Serial No. 288,039.

To all whom it may concern:

Be it known that I, ARTHUR MILLS, a citizen of the United States, residing at Sacramento, in the county of Sacramento and 5 State of California, have invented certain new and useful Improvements in Truck-Stakes, of which the following is a specification.

This invention relates to standards or 10 stakes for trucks, trailers and other vehicles and has for its object the provision of a comparatively simple and thoroughly efficient device of this character, capable of being readily inserted within or removed from a 15 receiving pocket, and which, when in position therein, will be effectually supported against accidental displacement without the employment of bolts, hooks or similar fastening devices.

20 The invention further aims to provide a truck stake having a resilient retaining strap surrounding the sides and bottom thereof and adapted to be compressed and frictionally engage the walls of the receiving pocket 25 when the stake is positioned therein.

The invention further contemplates novel 30 means for retaining the resilient strap in position on the stake or standard and means for permitting a limited lateral expansion 35 and contraction of the lower portion of the strap.

A further object is to provide a novel 40 form of receiving pocket for the lower end of the stake, and means carried by said stake 45 and adapted to bear against the upper end of the pocket for limiting the downward movement of the stake within said pocket.

A still further object of the invention is 45 generally to improve this class of devices so as to increase their utility, durability and 50 efficiency.

In the accompanying drawings:

Figure 1 is a perspective view of a stake or standard embodying the present invention showing the same in position on a 45 truck;

Fig. 2 is a longitudinal sectional view of the stake detached;

Fig. 3 is a transverse sectional view taken 50 on the line 3—3 of Fig. 2 and looking in the direction of the arrows;

Fig. 4 is a perspective view illustrating a modified form of receiving pocket.

Corresponding and like parts are referred 55 to in the following description and indicated

in all the views of the drawings by the same reference characters.

The improved stake or standard forming the subject-matter of the present invention is designed for attachment to trucks, trailers 60 and other vehicles and comprises a body portion 5, preferably formed of wood and having its lower end curved or rounded transversely, as indicated at 6. Secured to the opposite side faces of the body portion 5 65 near the lower portion thereof, are securing plates 7, the lower ends of which project longitudinally beyond the curved end 6 of the stake to form spaced longitudinal lips 8. The plates 7 are each preferably stamped 70 or otherwise formed from a single sheet of metal and are secured to the adjacent side faces of the stake by bolts, rivets or similar fastening devices 9. The metal constituting each plate 7 is cut or stamped to produce 75 oppositely disposed ears 10, which ears are bent laterally against the adjacent longitudinal edges of the standard 5 for engagement with a retaining strap, indicated at 11. The retaining strap 11 is preferably formed 80 of a single length of resilient metal, the intermediate portion of which is extended around and bears against the curved end 6 of the stake, while the opposite ends of the strap are interposed between the ears 10 and 85 the adjacent longitudinal edges of the stake with the terminals thereof curled or bent 90 into cylindrical form to produce stops 12 which bear against the upper edges of the ears 10 and serve to prevent accidental displacement of the strap, as best shown in Fig. 1 of the drawings. The side members 95 of the retaining strap 11 are normally spaced laterally from the adjacent longitudinal edges of the stake 5, as indicated at 13 in Fig. 2 of the drawings, so that when the stake is inserted in a receiving pocket the strap 11 will be compressed, thereby 100 causing the strap to frictionally engage the inner wall of the pocket and effectually retain the stake within said pocket without the employment of bolts, hooks or similar fastening devices. Each plate 7 is also preferably provided with oppositely disposed inwardly extending guide lugs 14 which bear 105 against the adjacent longitudinal edges of the strap at the bowed portion thereof and act as a combined guide and keeper for the strap.

The receiving pocket for the stake may be 110

of the usual construction, indicated at 15 in Fig. 4 of the drawings, but it is preferred to form the receiving pocket directly in one of the longitudinal sills 16 of the truck, as indicated by the numeral 17. Arranged within the pocket 17 in the sill 16 is a metallic casing or housing 18 provided with lateral attaching flanges 19 which are secured to the outer face of the sill 16 by screws or similar fastening devices 20. The sill 16 is preferably reinforced and strengthened by the provision of an outer bar or strap 21 which bears against the flanges 19 and constitutes the outer wall of the receiving pocket.

The lugs 14 not only serve to prevent undue lateral expansion of the retaining strap 11 but by engagement with the upper wall of the receiving pocket or casing 18 serve to limit the downward movement of the stake within said pocket as will be readily understood. As the lips 8 project longitudinally beyond the curved end 6 of the stake, it follows that said lips serve to center the retaining strap in position on the stake and prevent lateral displacement of the lower end thereof. Attention is here called to the fact that as the stake is inserted within its pocket the initial downward movement of the stake will cause the intermediate portion of the strap to frictionally bear against the curved wall 6 of the stake and a further movement thereof will compress the side walls of the strap so as to cause it to firmly contact with the wall of the pocket. Furthermore, owing to the resiliency of the retaining strap 12, wobbling or rattling of the stake within its pocket is prevented and liability of friction and wear on the parts correspondingly decreased. While it is preferred to have the upper ends of the retaining strap terminate at a point directly above the securing ears 10 it will, of course, be understood that the ends of said strap may, if desired, be continued longitudinally throughout the entire length of the stake or standard so as to assist in reinforcing the standard if found desirable or necessary in actual practice.

The devices may be made in different sizes and shapes and applied to any type of vehicle in which a device of this character is found desirable or applicable.

Having thus described the invention, what is claimed as new is:

1. The combination with a receiving pocket, of a stake having a resilient retaining strap secured thereto, the side walls of which are normally spaced from the adjacent edges of the stake and adapted to be compressed when inserted within the pocket for retaining the stake in position.

2. The combination with a receiving pocket, of a stake, and a resilient retaining strap having its intermediate portion extending around the lower end of the stake

and its opposite ends fastened to the longitudinal edges thereof, said strap being adapted to frictionally engage the walls of the pocket when the stake is inserted therein.

3. The combination with a receiving pocket, of a removable stake fitting within the pocket, side plates secured to the stake and provided with anchoring ears, and a resilient retaining strap fitting beneath said ears and having its intermediate portion extended around the bottom of the stake, said strap by engagement with the walls of the pocket serving to prevent accidental displacement of said stake.

4. The combination with a receiving pocket, of a stake fitting within the pocket, plates secured to the opposite faces of the stake and provided with ears fitting over the adjacent longitudinal edges of said stake, guide lugs extending from the plates in spaced relation to the ears, and a resilient retaining strap having its ends fitting beneath the ears and its intermediate portion extended between the lugs and fitting around the end of said stake.

5. The combination with a receiving pocket, of a stake fitting within the pocket, oppositely disposed plates secured to the side faces of the stake and having their ends projecting longitudinally beyond the lower ends of the stake to form spaced lips, and a resilient retaining strap extending around the bottom of the stake between the lips and having its ends anchored to the longitudinal edges of the stake, said strap being adapted to frictionally engage the walls of the pocket for preventing accidental displacement of the stake.

6. The combination with a receiving pocket, of a stake removably seated within said pocket, oppositely disposed plates secured to the stake and provided with in-turned ears, said plates being extended longitudinally beyond the lower end of the stake to form spaced lips, and a resilient retaining strap having its ends fitting beneath the ears and bent to form stop loops and its intermediate portion fitting around the lower end of the stake between the lips, the sides of the retaining strap being normally spaced from the adjacent edges of the stake and adapted to be compressed when inserted within the pocket for retaining the stake in position.

7. The combination with a receiving pocket, of a stake fitting within the pocket, side plates secured to the stake and provided with in-turned anchoring ears, a resilient retaining strap fitting beneath said ears and extending around the bottom of the stake, and guide lugs carried by the plates and adapted to bear against the upper edge of the pocket for limiting the downward movement of the stake within said pocket.

8. A stake for trucks comprising a body

portion having a transversely curved end and a resilient retaining strap having its intermediate portion extending around the curved end of the stake and its opposite ends normally bowed laterally in spaced relation to the adjacent longitudinal edges of the stake with its terminals anchored thereto.

9. A stake for trucks comprising a body portion having its lower end curved transversely, plates secured to the opposite side faces of the stake and having their ends projecting longitudinally beyond the curved end of said stake to form spaced lips, said plates being provided at their upper ends

with inwardly extended ears fitting over the adjacent longitudinal edges of the stake and at their lower ends formed with converging guide lugs, and a resilient retaining strap having its intermediate portion extending around the curved end of the stake between the lips and thence extended upwardly in spaced relation to the longitudinal edges of the stake and in contact with the guide lugs with the terminals of the strap extended beneath the ears and bent to form terminal stops contacting with said ears.

In testimony whereof I affix my signature.

ARTHUR MILLS. [L.S.]
